ROTARY DRILLING BIT

Roland R. Crum, Whittier, Calif.

6. Claims.

(Cl. 255-71)

This invention relates to a drilling bit of the rotary type; and particularly to one utilizing a plurality of toothed rotary cutters on an axis transverse to the drilling axis.

This type of apparatus is in general quite old, and has been in extensive use for years past. In many of them, there are two sets of cutters; one set comprising inner roller cutters or discs that are intended to bore on an inner circular area, and mounted for rotation on an axis perpendicular to the axis of bit rotation, and another set comprising outer roller cutters or discs, intended to bore on an outer annular zone, and mounted on axes that are also transverse to the bit axis, but angularly spaced from the axis of rotation of the inner discs. High drilling pressures are usually employed during rotation of the bit structure, and it is essential to ensure that the drilling elements such as the disc or rollers and the pins upon which they are mounted, may withstand such pressures successfully.

It is one of the objects of this invention to improve in general, bits of this character, and particularly by the aid of appropriately strengthened supporting structures for the roller cutter or discs. As an aid to this object, the bearings that sustain the radial or thrust forces are improved, and yet the assembly or replacement of the parts is performed easily.

the parts is performed easily.

Bit structures, especially when operating in earth bores where high fluid pressures may be encountered (as in oil wells), are often arranged to operate while submerged in a mud fluid. This fluid, as is well understood, is circulated so as to bring the disintegrated material to the top of the bore. The fluid is also passed through openings in the bit structure to flow past the cutting elements for keeping them from becoming loaded. It is another object of this invention to provide a simple and effective circulation of the fluid through the bit structure.

In furtherance of these objects, this invention contemplates the use of an arm by the aid of which the pins for the inner cutters are supported, that is, arranged to be placed between a pair of cutters, yet the cutters are so arranged that there is no discontinuity in the inner circular area being bored. It is thus another object of the invention to provide cutter supporting arms of this character.

This invention possesses many other advantages, and has other objects which may be made more easily apparent from a consideration of one embodiment of the invention. For this purpose there is shown a form in the drawings accom-

panying and forming part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a side elevation, partly in section, 10 of a drilling bit incorporating the invention;

Fig. 2 is a view similar to Fig. 1, but entirely in elevation:

15 Fig. 4 is a sectional view, taken along the plane

4-4 of Fig. 3, but with some of the roller supporting arms omitted; and

Fig. 5 is a pictorial view of one of the cutter supporting arms utilized in the invention.

1, the upper end of which is extended to form a threaded pipe coupling member 2 by the aid of which it may be appropriately connected to the lower end of a series of pipe lengths forming a drill string in the usual manner. In the present instance, bit head 1 supports a series of inner and outer roller cutters. The outer cutters 3 and 4 are shown in this instance as having axes 5 and 6 oblique to the axis of rotation 3 $\frac{1}{2}$ of the bit. These axes 5 and 6 incline inwardly and downwardly. The cutters 3 and 4 are each supported upon arms 7 and 8 joined to the body 1. Preferably the lower portions 9 and 10 of these arms may be welded on to the integral upper portions. As illustrated more in Figs. 1, 3 and 4, the upper portions may each be formed with a slot 11 into which the lower portions may dovetail.

Each of the lower portions 9 and 10 is provided with an integrally formed pin 12 (Fig. 1), extending inwardly of the arms and upon the axes 5 or 6 of the respective cutters 3 and 4. In the present instance each of these pins 12 is shown as tapered and having an intermediate threaded portion 13. The pin 12 serves as a support for the inner races of rolling bearing elements, adapted to sustain the radial and thrust forces. Thus adjacent the arm 9, there is a ball race 14 of annular shape, disposed around the pin 12. The cutters 3 and 4 are provided with appropriate cooperating outer ball races; and a series of balls 15 are interposed between these races to form a thrust ball bearing structure.

85 adjacent the free end of the pin 12, ball races are provided in which are inserted the series of

balls 16, forming a thrust ball bearing structure. The outer race is formed in the cutter 3 or 4; the inner race is formed on a member 19 hereinafter described.

Intermediate the ball bearings 15 and 16 there is a roller radial bearing structure 17. The outer race of this roller bearing structure is formed within the cutter 3 or 4. The inner races of the ball bearings for the balls 16 and the rollers 18 of the roller bearing are formed by the hollow, internally threaded retainer member 19. This member 19 is threaded on the threaded portion 13 of the pin 12, and may be screwed down tightly so that its end engages against the ball race 14. The member 19 may furthermore be welded to the pin 12, after assembly, by the depositing of welded material in a tapered recess 20 between the pin 12 and member 19.

The ball bearing structures at each end of the cutter 3 are intended mainly to take care of axial thrusts in the process of drilling. The intermediate roller bearings 18 are intended to provide a radial support for the associated cutter. The manner of assembly of the cutter 3 or 4 on its associated pin is simple. First the inner race 14 is placed on the pin 12; then the balls 15, balls 16 and rollers 17 are placed in the cutter and member 19 is telescoped into the cutter. Then the member 19 may be screwed onto pin 12.

For operating on the central portion of the bore, use is made of a series of inner roller cutters forming a cross roller cutter, shown to best advantage in Fig. 3. In the past it has been customary to provide pin supporting arms for these interior cutters, the arms being placed at the outer ends of radial pins. In order to provide a more rigid structure, the arms upon which the inner cutters are rotatably supported are so made in accordance with this invention that they support some of the inside cutters on one side of the arms, and some of the inside cutters on the other side of the arms. As in the case of the outer cutter supporting arms 1 and 8, the arms 21 and 22 (Figs. 3, 4 and 5) may be supported on the body 1 by the aid of welding. For this purpose the body 1 is provided with wide grooves or slots 23 and 24 having bottom sloping surfaces. In these slots the upper part of the arms 21 and 22 may be accommodated. The upper surface 25 of each of the arms 21 and 22 is arranged to abut an overhanging shoulder 26 (Figs. 2 and 3) formed on the head 1, in order to ensure accurate alignment when the arms 21 and 22 are dovetailed within the slots 23 and 24. Welded on metal 27 may overlap the contacting edges of the head 1 and the arms 21 and 22 at the top of the arms. Similarly, welded metal 28 and 29 (Fig. 4) may overlap the contacting edges of the sides of the arms and the sides of the bit head 1.

Since the structure of both arms 21 and 22 is identical, it is necessary to describe but one of them in detail. For this purpose the structure of arm 22 will now be set forth.

Arm 22, as shown most clearly in Figs. 3 and 5, is provided with integral inwardly projecting pin 30 having an axis radial to the axis 31 of the head 1. As shown most clearly in Fig. 3, the pin 30 which extends inwardly from the arm 22 approaches quite closely the other pin 30 of arm 21, at a point adjacent the center of the bit. These pins 30 are intended rotatably to support the conical inner cutters 32 and 33. For this purpose the pin 30 is provided with a wide groove 34 adjacent the inner side of the arm 22 to form the inner race for a series of rollers 35. The reduced

end 36 of the pin 30 provides inner races for the rows of balls 37 and 37' forming two thrust ball bearing structures. The outer races of all of the roller bearings are formed by the inner surfaces of the cutter structure 32, which has a portion of reduced diameter 32', forming a thrust surface between the rows of balls 37, 37'. Pin 30 has a collar 39 formed thereon, which is adapted to engage the outer row of balls 37' and prevent movement of cutter 32 outwardly along the pin. A still further reduced portion 38 of each pin provides a seat for a collar 39, for bracing the two pins against inward motion during the process of drilling. Similarly, collar 39 serves to prevent movement of the cutter 32 inwardly by engaging the row of balls 37. A corresponding arrangement prevents axial movement of cutter 33. Each of the cutters 32 and 33 is shown as tapered and having a helical-like series of cutter teeth 40.

In order to support a supplemental inside cutter, the arm 22 is further provided with an outwardly extending pin 41. This pin is disposed on an axis 42 which is inclined upwardly and inwardly toward the axis 31 of the bit. Upon this pin is supported the cutter 43. This cutter 43 is rotatably supported by a pair of end ball thrust bearings and an intermediate roller radial bearing. Thus adjacent the base of pin 41 there is an inner race 44 for a series of balls 45 forming the inner thrust bearing. The outer race for these balls 45 is provided by the cutter 43. The intermediate radial bearing rollers 46 are disposed between the inner race formed on a threaded member 47 threaded on the pin 41. This member 47 also forms the inner race for the outer thrust balls 48. Member 47 may be welded to the pin 41 by the addition of welded-on metal in the tapered space 49 disposed between pin 41 and the member 47.

The axis 42 is inclined in order to bring the lower inner edge 50 of the cutter 43 close to the outer edge of the cutter 32 so that all the inner cutters operate on a continuous inner circular area. By the provision of rotary cutters on each side of the arm 42, the forces imposed upon the arm 42 in the process of drilling are well balanced.

In order to protect the inclined cutters 43 from catching under irregularities in the wall of the well bore, as the bit is being withdrawn from the bore, a wing 51 may be formed integral with the upper part of the arm 22 and arranged to overlie the cutter 43. As shown most clearly in Figs. 2 and 4, this wing 51 has its upper surface steeply inclined to the vertical so as more effectively to perform its protecting function.

It is necessary to provide for the circulation of mud fluid through the drill string and past the various cutters. By the aid of the present structure this circulation is accomplished in a simple and effective manner. As is common, the bit head 1 is hollow, there being a chamber 52 within the bit head to permit the mud fluid to proceed downwardly. From this chamber 52 there extends a central narrow aperture 53 (Figs. 1 and 4) which extends for a considerable distance transversely of the bit head and which discharges mud fluid over the inner cutters 32 and 33. Also leading downwardly from the chamber 52 are a pair of shorter circulating apertures 54 and 55 discharging mud fluid adjacent the top of the outer cutters 3 and 4. The apertures 53, 54 and 55 are formed in the bottom wall 59 of the chamber 52. This wall is extended downwardly around the aperture 53, as shown most clearly in Fig. 1.

In order to discharge mud fluid adjacent the top of the cutters 43 supported on the outside of the arms 21 and 22, slanting apertures 56 and 57 are provided. These apertures extend not only through the bit head 1 but also through the top of the arms 21 and 22 to provide a discharge opening 58 (Fig. 4) adjacent the top of the corresponding cutter 43. Since the wings 51 are slanting as described in connection with Fig. 2, the discharge aperture 58 serves to discharge the mud fluid along the advancing edges of the cutters 43.

What I claim is:

1. In a rotary drill bit, a bit body, a pair of oppositely disposed arms attached to the body, means extending inwardly from each arm and integral therewith cooperating to form a substantially continuous transverse pin extending between the arms and having an axis perpendicular to the body axis, a pin extending outwardly from each arm and having an axis oblique to the axis of the transverse pin, and roller cutters mounted respectively on the pins, the cutters on the transverse pin providing a cutting surface extending substantially the entire distance between the arms.

2. In a rotary drill bit, a bit body, a pair of oppositely disposed arms attached to the body, means extending inwardly from each arm and integral therewith, cooperating to form a substantially continuous transverse pin extending between the arms and having an axis perpendicular to the body axis, a pin extending outwardly from each arm and having an axis oblique to the axis of the transverse pin, and roller cutters mounted respectively on the pins, the cutters on the transverse pin providing a cutting surface extending substantially the entire distance between the arms, the obliquity being such that the inner edge of the outer cutter at the bottom is close to the outer edge of the inner cutter at the bottom, whereby the cutters operate over a substantially continuous circular area.

3. In a rotary drilling bit, a body, two pairs of arms attached to the body, the arms of each pair being oppositely disposed about the axis of said body, one pair of arms carrying roller cutters arranged to operate over the outer zone of the well bore, and a cross roller cutter assembly extending transversely of the outer cutters and arranged to operate over substantially the entire well bore within said zone, the other pair of arms having pins serving to support the cross roller cutter assembly, said arms being positioned intermediate the ends of said cutter assembly.

4. In a rotary drilling bit, a body, two pairs of arms attached to the body, the arms of each pair being oppositely disposed about the axis of said body, one pair of arms carrying roller cutters arranged to operate over the outer zone of the well bore, means extending inwardly from each arm of the other pair and cooperating to form a substantially continuous pin between said arms, said pin extending transversely of the outer cutters, a pin extending outwardly from each arm and having an axis oblique to the said continuous pin, and roller cutters on the continuous pin as well as on the oblique pins, said last named cutters operating over substantially the entire well bore within said zone.

5. In a rotary drilling bit, a body, two pairs of arms attached to the body, the arms of each pair being oppositely disposed about the axis of said body, each arm of one pair having an inwardly and downwardly extending pin, roller cutters mounted on said pins arranged to operate over the outer zone of the well bore, each arm of the other pair having an inwardly as well as outwardly extending pin, the inwardly extending pins cooperating to form a continuous pin extending between said arms and transversely of the outer cutters, the outwardly extending pins being directed downwardly, and roller cutters on said continuous pin as well as on said outwardly extending pins, said cutters being arranged to operate over substantially the entire well bore within said zone.

6. In a rotary drill bit, a body, two pairs of arms attached to the body, the arms of each pair being oppositely disposed about the axis of said body, each arm of one pair having an inwardly and downwardly extending pin, a roller cutter on each of said pins, said cutters being arranged to operate over the outer zone of the well bore, each arm of the other pair having a pin extending outwardly and obliquely to the axis of said body, a roller cutter on each of the last mentioned pins, said cutters being arranged to operate over an intermediate zone adjoining said outer zone, said last mentioned arms also each having an inwardly extending pin, and a roller cutter on the last mentioned pin arranged to operate from the center of the well bore to said intermediate zone, the obliquity of said outwardly extending pins being such that the inner edges of the cutters supported thereon are at the bottom close to the outer edges of the respective inside cutters at the bottom.

ROLAND R. CRUM.
